UNITED STATES PATENT OFFICE.

ROSA MAY PICKARD, OF WILMETTE, ILLINOIS.

DESIGN FOR A BOOK END.

Application filed May 29, 1926. Serial No. 17,890. Term of patent 7 years.

To all whom it may concern:

Be it known that I, ROSA MAY PICKARD, a citizen of the United States, residing at Wilmette, in the county of Cook and State of Illinois, have invented a new, original, and ornamental Design for Book End, of which the following is a specification, reference being had to the accompanying drawing, forming part thereof.

Fig. 1 is a front elevational view of a book end showing my new design; and Fig. 2 is a side view thereof.

I claim:

The ornamental design for a book end as shown.

ROSA MAY PICKARD.
